BOTTLE SUPPORT

Edward Washington Napier, Wichita Falls, Tex.

Application September 3, 1935, Serial No. 39,081

3 Claims. (Cl. 225—22)

This invention relates to the class of supports and stands and pertains particularly to an improved means for supporting a bottle.

The primary object of the present invention is to provide an improved supporting means for bottles, particularly those of the type in which drinking water or distilled water is delivered for use in association with drinking fountains, whereby the contents may be discharged readily therefrom.

Another object of the invention is to provide a novel water bottle supporting means in which the bottle is firmly maintained in inverted position over and resting upon a dispensing cork to which a dispensing valve is attached.

A still further object of the invention is to provide a novel combined bottle stopper and dispensing means wherein the contents of the water bottle passes through the stopper to the dispensing means which is valve controlled.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view partially in side elevation and partially in section of the preferred embodiment of the invention.

Fig. 2 is a view in side elevation of a modification of the structure embodying the present invention.

Fig. 3 is a vertical sectional view thru the lower portion of the bottle and the central part of the stand structure showing the relation of the several parts.

Referring now more particularly to the drawing, the numeral 1 indicates a ring member which constitutes the upper or top part of one form of the bottle supporting means embodying the present invention. This ring member is secured to and maintained in position by legs 2, the lower ends of which are preferably outwardly flared and provided with suitable feet 3 which may be of rubber or any other suitable material.

Disposed at the vertical center of the stand is a centrally apertured plate or ring body 4 which is joined by the radial arms 5 with the legs 2. This central plate constitutes a supporting means

for a stopper or cork member 6 which is arranged in inverted position thereon and which has a central passage which receives an end of a pipe 7 which passes through the center of the plate 4 and which is joined at its lower end to an angle 5 coupling 8 with which is connected a faucet 9 of any suitable character.

Disposed vertically in the frame is a tube 10 which has its lower end extended through the pipe 7 into the coupling 8 and secured in an aperture 10 in the wall of the coupling upon the curved underside thereof so as to have access through the coupling wall with the air at the point 11. The cork or stopper 6 is tapered upwardly, as shown, and in placing the stand in use, a water bottle of the usual five-gallon capacity type is disposed in inverted position within the ring 1 in the manner illustrated so that the open mouth of the bottle receives and rests upon the stopper or cork 6 with the air tube 10 extending upwardly into the bottle to a point adjacent the bottom thereof. The bottle is indicated by the numeral 12 and, as shown, when it is in place upon the stopper 6, it will be encircled by the ring 1 at a point substantially midway of its ends. By opening the valve 9, a portion or all of the contents may be withdrawn through the pipe 7 and the withdrawn liquid will be replaced by air entering at the point 11 into the tube 10 and flowing therefrom into the upper end of the inverted bottle.

Figure 1 represents another and the preferred form of the invention. In this form there is provided a wall bracket which is indicated as a whole by the numeral 13 and which is preferably formed of channeled material, and has an elongated vertical portion 14 and an angularly turned lower portion or arm 15 which forms the support for the bottle, which is indicated by the numeral 16. The upper end of the vertical portion 14 is provided with suitable means for securing the bracket to a wall or other supporting structure, such means being indicated as a screw 17. Supported upon the horizontal arm 15 of the bracket is a plate 18 on which is disposed the inverted cork 19 which has a passage 20 extending therethrough. In this passage is a pipe 21, the lower end of which extends downwardly through an opening in the underlying portion of the bracket to receive a nut 22 which presses against the bracket and draws the nut 23 upon the upper end down against the upper end of the cork 19. The lower end of the pipe 21 has a faucet 24 attached thereto through which the contents of the bottle 16 are drawn, and the bottle is disposed in inverted position upon the bracket with the

cork 19 extending into the mouth thereof in the manner illustrated. In order to maintain the bottle properly in position, the upper end of the portion 14 of the bracket is provided with a ring 25 through which the bottom portion of the bottle is extended.

An air tube 26 has one end extended partially through the pipe 21 and provided with a lateral extension 27 which passes through the wall of the pipe into the area of the arm 15 of the channeled bracket lying beneath the plate 18. The other end of the tube extends upward through the pipe 21 and is adapted to position in the bottle 16 in the manner illustrated, so that it will have its upper end disposed in the water-free area of the bottle when the latter is placed on the bracket.

From the foregoing it will be apparent that the structures herein disclosed provide a simple but strong and steady means of maintaining a water bottle in the required inverted position for the discharge of its contents, and that because of the simplicity of the devices they may be economically produced and their construction is such that the bottles may be easily and quickly placed in the devices or removed therefrom.

What is claimed is:—

1. A device of the character described, comprising a vertically disposed bar having a bent laterally extended lower end portion, said portion having an upwardly directed channel formed longitudinally therein, an apertured plate supported on said channeled portion, a stopper supported on the plate and having a passage therethrough which is aligned with the aperture of the plate, a vertically arranged nipple passing through the stopper and the plate and extending downwardly through the channeled portion of the bar, a valve controlling the flow of fluid through and from the lower end of the nipple, and a vertical air tube having its lower end passing down through the nipple and extended laterally through the wall thereof to open into the channel beneath said plate.

2. A device of the character described com-

prising a vertically disposed elongated supporting member, an arm extending laterally from said supporting member, an apertured plate carried by said arm, a stopper element supported upon said plate and having a passage formed therethrough and aligned with the aperture of the plate, a nipple extending vertically through the apertured plate and through the stopper and having its lower end projecting below the plate, the nipple coupling the stopper and plate together, valve means controlling the flow of fluid through the nipple from the lower end thereof, an angle coupling connecting said valve means with the lower end of the nipple whereby the valve is disposed at one side of the longitudinal center of the nipple, and a vertical air tube having its lower end passing through said nipple and extending through and secured in the wall of said angle coupling for communication with the atmosphere at the lower side of the coupling.

3. A structure as described, comprising a vertically disposed bar-like member, a bottle encircling ring carried upon the upper end of said member, a lateral extension forming a part of the member and disposed beneath the ring, a centrally apertured plate supported by said lateral extension on the axial center of the ring, a centrally apertured stopper supported on the plate with its aperture aligned with the plate aperture, a short pipe of constant diameter throughout extending through the stopper passage and through the plate and projecting below the latter, an air tube disposed vertically and having its lower part passing through the pipe and open to the atmosphere below the plate, the tube throughout its length constituting a unit separate from and separable from the pipe, and a faucet coupled with the lower end of the pipe, said stopper being adapted to be secured in the mouth of a bottle inverted in the ring and said air tube extending upwardly to a point adjacent the bottom of the inverted bottle.

EDWARD WASHINGTON NAPIER.
